UNITED STATES PATENT OFFICE

128,623

DESIGN FOR A ROOFING AND LINOLEUM KNIFE

George W. Dorcas, Denver, Colo.

Application March 10, 1941, Serial No. 99,452

Term of patent 14 years

To all whom it may concern:

Be it known that I, George W. Dorcas, a citizen of the United States, residing in the city and county of Denver and State of Colorado, have invented a new, original, and ornamental Design for a Roofing and Linoleum Knife, of which the following is a specification, reference being had to the accompanying drawing, forming part thereof.

In the drawing:

Figure 1 is a plan view of a roofing and linoleum knife showing my new design; and

Figure 2 is a side elevation thereof.

The essential feature of my design resides in the specific shape, proportion and arrangement of the blade in combination with a handle of the specific configuration disclosed in the drawing.

I claim:

The ornamental design for a roofing and linoleum knife, as shown and described.

GEORGE W. DORCAS.
